CLAIM

The ornamental design for a handle for a steam iron, as shown and described.

DESCRIPTION

FIG. 1 is a top, front perspective view of a handle for a steam iron showing my new design, wherein the various elements are shaded to indicate contrasting surfaces, the oval-shaped element is stippled to indicate a contrasting switch, and the broken-line showing of the iron is for illustrative purposes only and forms no part of the claimed design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear elevational view thereof; and

FIG. 7 is a front elevational view thereof.
